UNITED STATES PATENT OFFICE.

IRENE H. RUNDQUIST, OF CHICAGO, ILLINOIS.

DESIGN FOR A DOLL.

56,891.

Specification for Design.

Patented Jan. 4, 1921.

Application filed October 22, 1919. Serial No. 332,567. Term of patent 7 years.

To all whom it may concern:

Be it known that I, IRENE HUND RUNDQUIST, a citizen of the United States, residing at Chicago, in the county of Cook and State of Illinois, have invented a new, original, and ornamental Design for Dolls, of which the following is a specification, reference being had to the accompanying drawing, forming part thereof.

Fig. 2 is a rear elevation of the doll shown in Fig. 1.

I claim:

The ornamental design for a doll, as shown.

IRENE H. RUNDQUIST.
